UNITED STATES PATENT OFFICE.

JOSEPH ALGER, OF BROCKTON, MASSACHUSETTS, ASSIGNOR OF ONE-HALF TO HIMSELF
AND ONE-HALF TO ARTHUR H. ALGER, OF BROCKTON, MASSACHUSETTS.

BOX-COVERING MACHINE.

1,028,421.

Specification of Letters Patent.

Patented June 4, 1912.

Application filed June 12, 1908. Serial No. 438,146.

To all whom it may concern:

Be it known that I, JOSEPH ALGER, a citizen of the United States, residing at Brockton, county of Plymouth, Commonwealth of Massachusetts, have invented certain new and useful Improvements in Box-Covering Machines, of which the following is a specification.

This invention relates to machines for covering boxes and particularly to that class of machines which apply the covering to the box in the form of a blank which is folded about the box and attached thereto. There are two principal styles of boxes which are 15 papered in this way, the one a plain box with the usual rectangular or squared corners and sides, and the other a box having about its top or bottom edges, or about both, an extension or flange. The papering of 20 these two types of boxes in a single machine presents a difficult problem as the differences in form and the action in handling of the coverings requires a great scope of adaptability in the mechanisms of the device.

In my former Patent No. 820,166 I disclosed a machine of this general nature and while this machine is operative, it is subject to various limitations which it is the 30 object of the present invention to overcome as well as to provide new features and elements and other general improvements.

In my present invention I have provided a new means for forming the turn in the 35 cover at the ends of the box, an improved system of tucking in and turning the paper at the edges, an improved driving system, centering, locating mechanisms, and more complete arrangements for adjustment and 40 interchange with various other constructions and arrangements of parts which are embodied in the machine to be more fully hereinafter described as illustrative of my invention.

Throughout the specification and drawings, in which this embodiment is set forth; like reference numerals indicate corresponding parts, and in the drawings:

Figure 1 is a front view of the machine, 50 Fig. 2, a side view from the right of Fig. 1, Fig. 3, a plan view of the machine with the superstructure removed, Fig. 4, a detail plan in partial section of centering device and internal brush arrangement, Fig. 5, detail 55 tail view of end turner and operating mech-

anism, in upward position. Fig. 6, a front sectional detail of the folder and internal pasting mechanisms, Fig. 7, a detail of the folders applied to an extension edge box, Fig. 8, a plan view of the box support 30 shown in Fig. 7 with a side folder swung up, and Figs. 9, 10, 11, details of brush structure.

1 is a bed supported upon legs 2.

3 are uprights on the bed supporting a 65 frame 4 on which there is mounted for vertical reciprocation a tubular slide 5, in which is a placer rod 6 slidable, but held from turning therein by a key 8 which is pinned to the rod 6 and works in a slot 9 70 in the slide 5.

6¹ is an adjustable stop on the rod 6 which is adapted to engage a stop 15¹ on a support 16.

5¹ is a cap on the end of the tubular slide 75 5 between which cap and the key 8 is contained a spring 10 which allows a continued movement of the slide 5 after the placer 11, carried on the end of the rod 6, reaches the bottom of the box B as it rests on the support 12.

13 is a head supported on the slide 5 having slots 13¹ in which are adjustably bolted brush supports 14 carrying brush plates 15. Upon the return of the slide the spring 10 85 holds the placer down upon the bottom of the box until the brushes are withdrawn, thus assuring their clearance from the box. On the support 12 is a removable block which may be varied as will be hereinafter 90 described for the accommodation of different types of boxes. The support 12 is adjustable on a threaded standard 12¹ by lock nuts 12².

Referring to Figs. 3 and 5, 21 are slide- 95 ways in which are adjustably mounted supports 22 which carry the folders 24 and 25 which are hinged thereto, as indicated at 23, 24 being the end folders and 25 being the side folders. As shown, the folders 24 100 and 25 are oppositely mounted and are operated by rods 26 and 27 respectively set in yokes 28 and 29 which are in turn controlled by suitable connections with cam grooves 28¹ and 29¹ in the cams 94 and 93. The slide 5 is operated by a lever 31 which is rocked by a link 32 from a bell crank 33 controlled by a connection 34 with a cam groove 34¹ in the cam 91. 40 are supporting slideways 105 adjustably mounted on the bed 1 for guid- 110

ing the end turner slides 41 on which are adjustably mounted end turning arms 42. To these arms 42 are adjustably attached blades 43 which through the slot 44 and bolt 5 45 may be set at any relative angle to the arms 42 which are capable of adjustment on the slides 41 through the slots 46 and the bolts 47. The slideways 40 are formed at their lower ends with plates 40¹ which are 10 slotted at 40² and through these slots are set bolts 49 which are tapped into the bed 1. By loosening the bolts 49 the slides 40 may be laterally adjusted to any position desired within the limits of the slots 40². The slides 15 41 at the front and rear of the machine are both operated by the levers 50 pivoted at 51 and rocked by the connections 52 with the cam slots 52¹ in the cams 91 and 92.

Returning to the construction of the folding device and referring to Figs. 3, 5, and 20 6, the folders 24 and 25 are slotted for the adjustable mounting of folder plates 64 and 65. These plates are grooved at their lateral edges and in these grooves are mounted adjustable blocks 66 between which intersticed 25 turners 67 are stretched to bring the covering paper over the edge of the box or cover. These turners are preferably formed as spirals and if formed of wire have a yielding 30 quality due to their springlike nature and may thus accommodate themselves to any irregularities and yield. It is to be noted that these turners enter, in their operative position, the path of the brushes 15 35 but the brush readily enters the interstices of the laterally exposed spiral and passes through it, carrying with it the paper which the turner has brought over the edge of the box and pressing it against the inside of the 40 box wall to which it attaches itself by the glue coating which has been applied. Through the vertical adjustability of the blocks 66 the turner 67 may be raised or lowered to pass over the edge of boxes or 45 covers of varied depths.

In the operation of a machine on plain boxes or on those formed with what is known as the package end, it is of great importance that the fold in the paper at the end of the 50 box be started at just the right angle. What this angle is depends on the height of the box and the nature of the paper. Some papers fold readily but are liable to tear if the angle of the folders is not just right, 55 while other papers are stronger, but, the fold does not run so readily and the blades are apt to punch through or tear if the folder does not approach at the proper angle. The adjustment of the slides 40, the blades 43 60 and the arms 42 relative to the slides 41 to secure the proper angle of approach is a matter of great importance and this is made possible by the intermediate arm which further permits the blade to be set so that its 65 forward end 43¹ will always travel and be

maintained in an approximately vertical position, and so that the oppositely disposed blade ends will almost, but not quite, meet at the central point of the end of the box. In the operation upon extension edge boxes the 70 blade 43 is replaced by a brush 48 which turns in the corner flap of the blank used for this purpose. This blank is shown and described in Letters Patent No. 781,766 the flap being lettered therein as C¹. 75

The operation of the machine is substantially the same in the handling of the two different types of boxes but in the case of the plain box or package end type the box support is formed as a holder 75 (see Figs. 2, 3, and 5,) with sides of stiff material such as sole leather which receive the box with its covering blank applied to its bottom and hold it with the blank all turned up at the sides. It is in this position that the operative places it in the machine. In working upon extension edge boxes the support is formed as a plain block made somewhat thinner than that used on the plain boxes and, consequently, having its upper surface 80 in a plane lower than the bottom edge of the folder plates 64 and 65. This permits the adjustment of the folder plates so that they will turn up on the margin of the block and bear down upon the extension of the box 95 resting thereon, as shown in former Patent No. 820,166.

In Figs. 1, 2, 3, and 6 it will be noted that I have shown a means 70 for drawing up the paper in advance of the folders. This 100 I have designated as a belt in my former Patent No. 851,052 in which it is lettered L. This belt 70 is attached to the support 12 and extends from the ends, being held outwardly and in advance of the folders by 105 cords 71 which pass through arms 72 and are yieldingly held by springs 73. This permits a play of the connections and a maintenance of the tension on the belt 70 so that it will advance to the box carrying the paper 110 with a yielding but even tension.

With the machine positioned as in Fig. 1 and supposing that the box to be covered is of the plain type or a top desired to be finished in the package end style, the operator takes a box (or top, as the case may be) to which a blank previously gummed and properly located on the bottom (or on the top, in the case of a box top), and thrusts it within the holder 75 which supports the 115 flaps of the blank which are to cover the side, in an upright position. The foot lever 80 is now depressed against the action of the spring 81 and the clutch on the power shaft set to actuate the main shaft 90 of the machine. On this shaft are mounted the cams 91, 92, 93, 94, and 95, of which 95 controls the placer 11 and brush 15 mechanisms, through the connections 31, 32, 33; 91 the 120 end turner slides 41 at the front of the ma- 125 chine. On this shaft are mounted the cams 91, 92, 93, 94, and 95, of which 95 controls the placer 11 and brush 15 mechanisms, through the connections 31, 32, 33; 91 the 130 end turner slides 41 at the front of the ma-

chine through the lever 50; 93 the side folders 25, through yoke 29 and rods 27; 94 the end folders 24, through the yoke 28 and the rods 26; and, 92 the end turners at the rear of the machine through the rear lever 50. These cams are so relatively timed that the parts operate in the following order. As the machine starts from the position shown in Fig. 1 the slide 5 quickly drops until the 10 placer 11 strikes the bottom of the box B. This placer 11 has a pair of adjustable arms 11¹ pivoted in the end of the placer rod 6 at 11². These arms 11¹ normally drop from the horizontal slightly, thus slightly shortening their available total distance between 15 ends. As the placer strikes the bottom of the box (or top) the arms are thereby brought into horizontal position and the ends thereby brought apart touching the 20 ends of the box to move it in one direction or the other endwise to properly center it with reference to the end folders. As soon as this is done the side folders 25 swing up into position. The end turners then advance 25 simultaneously from the front and rear of the machine to bring their properly adjusted blades 43 past the ends of the box to turn in the paper around the end corners folding and creasing it neatly. Just as these blades 30 43 are withdrawing, the end folders 24 swing up to press their plates 64 against the ends of the box. The belt 70 which travels in advance of these folders catches the folded covering and draws it up against the box 35 end so that as the plate 64 finally bears against the box the covering is all laid in place. As soon as the blades 43 are withdrawn the end folders 24 swing up into position closing in the box on the sides and completing the inclosure of it. In this position the turners 64 project over the edges of the 40 box and press the edges of the blank inward in a horizontal position. The slide now continues its movement downward slightly 45 compressing the spring 10 until the brushes 15 have passed through the interstices of the turner and pressed the edge of the covering paper against the inside of the box walls. The slide 5 then lifts carrying the brushes 50 out of the box and removing the placer and the side folders are dropped back to release the box and leave it free for removal. In operating upon an extension edge box the movements of the parts are the same but, 55 as explained above, the machine is in this case fitted with a different support for the box and blank. This support comprises a block 100 of the size of the box bottom and extension. The side edges of this block are 60 provided with centering fingers 101 pivoted at 102 and normally held with the centering point 103 above the plane of the block 100 by a spring 104. The points 103 therefore assure the proper location of the box laterally, while the placer 11 locates it longitudi-

nally. The bottom edge of the side folder strikes on the projecting point 103 of the finger 101 but the finger swings down and yields so that the plates 65 are allowed to assume their proper position against the side 70 of the box. In the operation upon extension edge boxes the end turner blade 43 is replaced by a brush 48 which is adjustably mounted on the adjustable connection 42. This brush in addition to making the turn about the corner of the box, presses and pastes the gummed blank of the extension covering against the end of the box. (See Fig. 9).

I claim:

1. In a box covering machine means for supporting a box and covering blank, an inclined slideway in line with the end of the box support, a slide movable in said slideway to approach said support, an arm adjustably supported on said slide and means adjustably supported on said arm to fold a blank about the end of a box. 80

2. In a box covering machine means for supporting a box and covering blank, an inclined slideway in line with the end of the box support, a slide movable in said slideway to approach said support, and means adjustably supported on said slide to fold the blank about the end of the box. 90

3. In a box covering machine removable means for supporting boxes and covering blanks, a laterally adjustable slideway in line with the ends of the box support, a slide movable in said slideway to approach said support, and means on said slide to fold a blank about the ends of a box. 95

4. In a box covering machine a support for a box and covering blank, a vertically descending placer for locating said box on 105 said support, said placer comprising a pair of adjustable arms normally depending from a right line but movable into alinement upon reaching the bottom of the box.

5. In a box covering machine a support 110 for a box and covering blank, a vertically descending slide, lateral box contacting means on said slide, and means for laterally adjusting said box on said support, said lateral box adjusting means being yieldingly 115 carried in normal advance of said box contacting means.

6. In a box covering machine, a support for a box and covering blank, a vertically descending slide, lateral box contacting 120 means on said slide, normally advanced means for the lateral adjustment of said box on said support and means for operating said slide and said lateral adjusting means, said box contacting means being adapted to 125 overtake said lateral adjusting means after the box is adjusted.

7. In a machine for covering paper boxes a support for a box and covering material, a turner for bringing the covering material 130

over the edge of the box, a presser to bring said covering material against the interior of said box, said turner and presser being relatively movable and having openings to permit the passage of one through the other and means for relatively moving said support and presser.

8. In a machine for covering paper boxes a support for a box and covering material, a vertically opened turner for bringing the covering material over the edge of the box, vertically separable means for bringing said covering material against the interior of said box, said two means last named being relatively movable and means for relatively moving said support and presser.

9. In a machine for covering paper boxes means for supporting a box and covering material, a folder mounted to move relative to said support, a turner on the face of said folder for bringing the covering material over the edge of the box, a presser to bring said covering material against the interior of said box said turner and said presser being relatively movable and having openings to permit the passage of one through the other said support and presser being relatively movable.

10. In a machine for covering paper boxes means for supporting a box and covering material, a folder mounted to move relative to said support, a turner adjustably mounted on the face of said folder for bringing the covering material over the edge of the box, a presser to bring said covering material against the interior of said box, said turner and presser being relatively movable and having openings to permit the passage of one through the other and said support and presser being also relatively movable.

11. In a machine for covering paper boxes a support for a box and covering, a brush for pasting the covering within the box, means for folding the covering about the box, an intersticed turner on said means for holding the covering over the edge of the box, said brush and turner being relatively movable, and means for relatively moving said brush and support.

50 12. In a machine for covering paper boxes a support for a box and covering, a brush for pasting the covering within the box, means for folding the covering about the box, an intersticed turner adjustably mounted on means for holding the covering over the edge of the box, said brush and turner being relatively movable, and means for relatively moving said brush and support.

13. In a machine for covering paper boxes a support for a box and covering, a brush for pasting the covering within the box, a folder mounted to be moved relative to said support, an intersticed turner on said folder for holding the covering over the edge of the box, said brush and turner being relatively

tively movable, and means for moving said brush through said turner to bring the coverings against the inside of the box.

14. In a machine for covering paper boxes a support for a box and covering, a brush for pasting the covering within the box, a folder mounted to be moved relative to said support, an intersticed turner adjustably mounted on said folder for holding the covering over the edge of a box and means for moving said brush through said turner to bring the coverings against the inside of the box.

15. In a machine for covering paper boxes means for supporting a box and covering material, a turner having openings therein for bringing the covering material over the edge of the box and means adapted to pass through said openings in said turner to bring said covering material against the interior of said box.

16. In a machine for covering paper boxes means for supporting a box and covering material, a vertically adjustable turner for bringing the covering material over the edge of a box and a presser to bring said covering material against the interior of said box, said turner and presser having openings to permit the passage of one through the other.

17. In a machine for covering paper boxes means for supporting a box and covering material, a turner movable relative to said support to bring the covering material over the edge of the box and a presser to bring said covering material against the interior of said box, said turner and presser having openings to permit the passage of one through the other.

18. In a machine for covering paper boxes a brush for pasting the covering within the box and an intersticed turner for holding the covering over the edge of the box, said brush and turner being relatively movable.

19. In a machine for covering paper boxes a brush for pasting the covering within the box and an intersticed turner for bringing the covering over the edge of the box in advance of said brush, said brush and turner being relatively movable.

20. In a machine for covering paper boxes a support for the box and covering material, a brush for pasting the covering within the box and an intersticed turner for holding the covering over the edge of the box, said brush and turner being relatively movable, and means for relatively moving said support and brush.

21. In a machine for covering paper boxes means for supporting a box and covering material, a turner having openings therein adapted to have lateral movement to bring the covering material over the edge of the box and vertically active a presser adapted to pass through said turner to bring said covering material against the interior of

said box said turner and presser being relatively movable and having openings to permit the passage of one through the other.

22. In a machine for covering paper boxes
5 a support for a box and covering paper, means for folding covering paper about the box supported for movement relative thereto, flexible means for drawing up the paper in advance of the folding means, attached at
10 one end to said support and having its opposite end yieldingly held and having a sliding engagement with said folder intermediate of its ends.

23. In a machine for covering paper boxes
15 a support for a box and covering paper, means for folding covering paper about the box mounted to be swung relative thereto, flexible means for drawing up the paper in advance of the covering means attached at
20 one end to said support and having its opposite end yieldingly held and means on said folder for sliding engagement with said flexible means intermediate of its ends.

24. In a machine for covering paper boxes

a support for a box and covering paper, 25
folders mounted to swing relatively to said support, flexible means for drawing up the paper in advance of said folders, said flexible means being attached at one end to the support and connected at its opposite end by 30
a cord to the frame and means on said folders for slidably engaging said cord.

25. In a machine for covering paper boxes
a support for a box and covering paper, a 35
folder mounted to swing relatively to said support, said folder having an eye therethrough, flexible means for drawing up the paper in advance of said folder, said flexible means being attached at one end to the support and connected at its opposite end by a 40
cord to the frame, said cord passing through said eye.

In testimony whereof, I affix my signature in presence of two witnesses.

JOSEPH ALGER.
